GATE FOR DIE CASTING

Nathan Lester, Cleveland Heights, Ohio, assignor
to The Lester Engineering Company, Cleve-
land, Ohio, a corporation of Ohio

Application April 7, 1937, Serial No. 135,522

1 Claim. (Cl. 22—155)

The present invention relates to a new and improved form of construction for a gate in a die casting mold. My invention is applicable to be used in conjunction with permanent molds for the casting of metallic and non-metallic metals such as non-ferrous alloys and plastics, under pressure.

Heretofore it has been necessary in the die casting art to provide a gate or a channel through which the molten or liquid material to be cast flows into the mold cavity, and such a gate, upon solidification of the casting, not only results in a relatively large "slug" of waste material which must be removed from the casting, but also required the provision of a large and extra cavity in the die blocks which form the mold so that the gate slug can be removed from the die cavity along with the casting. A gate or a relatively large channel leading into the die cavity and for the reception of excess casting material is of course necessary in such casting operations.

It is the general object and nature of my present invention to provide construction for the presence of such a gate or relatively large inlet channel, but at the same time to provide means whereby the excess metal residuary in such a gate or inlet channel does not become a part of the resultant solidified casting and is maintained in a liquid or non-solidified form, so that such excess material is available for the next "shot" or subsequent casting operation. My invention therefore possesses the novel advantages and produces the new results of eliminating waste material, the necessity for extra handling, removal of gate slugs and remelting of such waste material, as well as permitting the easier and more convenient removal of the casting and eliminating the necessity of a special gate slug cavity in the die blocks.

Briefly outlined, my invention consists in the provision of a gate or inlet channel leading to the die cavity together with heating means located adjacent such gate, which heating means function to maintain the residuary or excess material in the gate in a liquid state while the casting solidifies and thereby prevents such gate slug from becoming a part of the resultant casting.

To the accomplishment of the foregoing and related ends, said invention then, consists of the means hereinafter fully described and particularly pointed out in the claim.

The annexed drawing and the following description set forth in detail certain structure embodying the invention, such disclosed means con-

stituting, however, but one of various structural forms in which the principle of the invention may be used.

In said annexed drawing:

Fig. 1 is a sectional view taken through the die blocks forming the die casting cavity and illustrating the construction embodying the principle of my invention; Fig. 2 is an elevational view of the face of the left hand die block shown in Fig. 1; and Fig. 3 is an elevational view of the face of the right hand die block shown in Fig. 1.

Now referring more particularly to the drawing, there are shown therein a die block 1 which is adapted to meet with a die block 2 along the parting line P. These die blocks of course are mounted in a die casting machine (not shown) and supported upon the horizontal bars 3 in such a manner that the die block 2 is movable into and out of engagement with the die block 1. A plurality of die cavities 4 are formed in the face of the die block 1 and these cavities are placed in communication with a central point by means of the distributing channels 5 in the die block 2. The channels 5, although not technically a part of the view as Fig. 2 is taken, are nevertheless shown in dotted lines for the purpose of more conveniently illustrating the construction. Core pieces 6 are carried in the die block 2 and their extending ends, or left hand ends as seen in Fig. 1, form the male part of the die cavity 4. Ejector pins 7 are mounted in the core pieces 6, and an ejector pin 8 is also mounted in the die block 2 at the point of central convergence of the channels 5. As is well understood in the art, these ejector pins function to force or eject the casting away from the face of the die block 2 as the latter is moved to open position with respect to the die block 1.

A gate or inlet channel 9 is provided in the die block 1 and leads to the opening 9' located substantially at the central portion of the casting cavity. The other end of the gate 9 is in communication with the passage in the connector 10 which in turn leads from the pressure casting source of the die casting machine. The connector 10 has a semi-spherical end surface which fits in the corresponding convex recess 11 in the die block 1.

The bottom walls of the gate 9 are formed by an insert 12 attached to the die block 1, and this insert 12 has a central passage for the reception of a heating element such as an electrical resistance coil. In this manner the walls of the gate or inlet channel 9 are so heated as to pre-

vent the excess material in the gate 9 from becoming solidified during the time that the material solidifies in the cavities 4. It will also be noted that the walls of the gate 9 are horizontally inclined in an upward direction toward its discharge end 9', whereby the excess metal in the gate 9 will tend to run back down into the connector 10 and not out toward the face of the die block 1 as the casting pressure is relieved and as 10 the die blocks 1 and 2 are moved to open position.

Other modes of applying the principle of my invention may be employed instead of the one explained, change being made as regards the structure herein disclosed, provided the means stated 15

by the following claim or the equivalent of such stated means be employed.

I therefore particularly point out and distinctly claim as my invention:

In a casting die, the combination of separable die blocks forming a die cavity, a gate through one of said blocks leading to said cavity, and an insert having an outer wall constructed and arranged to lie flush with and extend across the parting line face of said one of said blocks, and having an inner wall arranged to form a horizontally inclined bottom wall of said gate, said insert being hollow for the reception of a heating element.

NATHAN LESTER. 15
